ILLUMINABLE DISPLAY STAND

Lawrence W. Patterson, Santa Ana, Calif.

Application November 18, 1957, Serial No. 48,502

Term of patent 14 years

(Cl. D80—9)

Fig. 1 is a front elevational view of my new design for illuminable display stand;

Fig. 2 is a side elevational view thereof; and

Fig. 3 is a perspective view taken from the rear and from below the stand.

The dominant features of the design reside in the portions shown in full lines.

I claim:

The ornamental design for an illuminable display stand, as shown and described.
